1

This invention relates to thermionic valve apparatus, for generating high voltage impulses of short duration.

It is sometimes necessary to operate thermionic valve apparatus for relatively short periods of time at relatively long time intervals. Such a requirement arises, for example, in the case of transmitting apparatus for radiating short bursts of radio frequency oscillations in the detection and location of reflecting objects such as aircraft.

Intermittent operation of this kind may conveniently be brought about by applying the requisite polarizing voltages to the valves only during the time periods when it is desired that the apparatus shall operate. Thus, the anode voltage may be applied to the valves only during the desired operative periods, and it is therefore desirable to have some convenient means for generating the required anode voltage. Moreover, as it is found that in such circumstances valves are not damaged by the application of polarizing voltages greatly exceeding those which are permissible for continuous operation, it is advantageous to generate extremely high voltages during the operative periods.

It is an object of the present invention to provide apparatus adapted to generate high voltage impulses of short duration.

It is a further object of the present invention to provide apparatus for generating short bursts of radio frequency oscillations in which residual oscillations are suppressed.

According to one feature of the present invention there is provided apparatus for applying to a load high voltage impulses of short duration at time intervals long in relation to said short duration, said apparatus comprising a thermionic valve (or valves) arranged so as normally to be non-conductive, an inductance connected in the output circuit of said valve and means for periodically causing said valve to conduct for a predetermined time period substantially shorter than said time intervals so as to build up a current in said inductance and for thereafter causing said valve to return to the non-conducting state so as to set up said high voltage impulse across said inductance, and means for feeding said impulses to said load.

Preferably, the valve is rendered conducting and non-conducting in the required manner by applying between a control electrode of said valve and its cathode suitable biasing pulses.

Said inductance may constitute the whole or a part of the series inductive elements of a time delay network terminated at one end by an im-

2

pedance, preferably low in value, such that in operation reflection occurs, and terminated at its other end in a substantially reflectionless manner by said load.

5 Said valve may conveniently be provided with a screening grid in which case a series resistance and/or a resonant circuit may be connected between said screening grid and the source of positive potential for polarizing said grid so as to limit the anode current of said valve during the preliminary portion of said predetermined time periods but to cause the potential of said screening grid to rise rapidly to a maximum towards the end of said predetermined time periods.

10 15 If desired, said biasing voltage may be of saw-tooth waveform, and additional biasing means may be provided for applying additional negative bias to the control electrode of said valve when said high voltage impulse is generated so as to maintain said valve non-conducting.

Said apparatus may conveniently be used to provide polarizing voltages in apparatus for generating short bursts of radio frequency oscillations.

20 25 Now we have found that when apparatus of the kind referred to above is operated, the generated oscillations do not cease immediately at the end of the high voltage polarizing impulse, since the oscillations set up in the oscillatory circuits of the apparatus persist for a time governed by the decrement of these circuits. It will be appreciated that the persistence of the oscillations may be undesirable if it is desired to detect reflecting objects at close range, since the reflected signal will return in a very short time and may be masked by the residual oscillations of the transmitter.

According to another feature of the present invention, therefore, there is provided apparatus for generating short bursts of radio frequency oscillations including a valve and apparatus incorporating any or all of the above-mentioned features for applying a high voltage impulse between the anode and cathode of said valve so as to cause the generation of said oscillations in which means are provided for applying a positive voltage impulse, after a time delay of the same order as the duration of said high voltage impulse between the grid and cathode of said valve of said oscillator whereby said oscillations are more rapidly damped after the cessation of said impulse by grid current damping.

Said means may conveniently comprise an inductive potentiometer connected in shunt with said inductance, an intermediate tapping point

3 on said potentiometer being connected, if desired, through a time delay network, to the control electrode of said valve of said oscillator.

In order that the invention may be more fully understood it will now be described in greater detail with reference to the drawings in which

Figure 1 is a circuit diagram of a pulse generator constructed according to one embodiment of the invention,

Figure 2 is a detail of a circuit for applying the switching pulses to the circuit of Figure 1,

Figure 3 is a circuit diagram of a pulse generator constructed according to another embodiment of the invention, and

Figure 4 is a circuit diagram that illustrates a modification of the apparatus shown in Fig. 3.

Referring now to Figure 1 it will be seen that a pair of pentode valves 3 is employed in a push-pull radio frequency amplifier. The control electrodes of the valve 3 are connected to a tuned circuit 4 which is arranged to be supplied with radio frequency energy from a coil 5. The anodes of the valves 3 are connected to a tuned output circuit 6, the inductance of which is coupled to a coil 7 which serves to apply the output of the generator to, for example, an aerial. It will be assumed that the circuit arrangement shown is to be arranged to generate bursts of radio frequency oscillations, the approximate duration of the bursts being 0.5 microsecond and the bursts recurring every 200 microseconds.

For this purpose, means are provided for applying suitable polarizing voltages to the electrodes of the valves 3 so as to make them operative to feed said radio oscillations to said aerial only during the time intervals when it is desired that said oscillations shall be transmitted. By reason of the fact that the valves 3 are thus only operated intermittently, very much higher polarizing voltages may be applied than could be used for continuous operation of such valves. These high polarizing voltages are provided by means of the inductance 8 connected between the anode of a valve 13 and its source of anode voltage (1000 volts) indicated by the arrow 9 and shunted by the bypass condenser 10. The valve 13 is normally non-conducting, but means (not shown), such as a multivibrator, are provided for applying a positive biassing voltage pulse to the control electrode of the valve 13 so as to render said valve conducting for a predetermined time period and thereafter to cause said valve suddenly to cease conducting so as to set up a high voltage impulse, which may have a peak voltage of 7000 volts, across said inductance 8. Said biassing pulse may conveniently have a duration of 4 microseconds and may be arranged to terminate just before each 0.5 microsecond interval during which oscillations are to be radiated.

The high voltage impulse set up across the inductance 8 is applied to the valves 3 so as to cause them to become operative. The upper end of the inductance 8 is connected to the center point of the tuning inductance of the tuned circuit 6 and thence to the anodes of the valves 3, so that the high voltage impulse is applied between the anode and cathode of each of the valves 3. A suitable tapping on the inductance 8 is connected to the screen grids of the valves 3 so that an appropriate potential is applied to these electrodes simultaneously with the application of the anode voltage. Further, the center tap of the tuning inductance of the tuned circuit 4 is connected to a still lower tapping on the inductance 8 via the blocking condenser 12, so that

a standing negative bias which is applied to the control electrodes of the valves 3 via the choke 11 from an external source of bias (not shown) may be neutralized to bring said control electrodes to a suitable operating potential when the high voltage impulse is developed across the inductance 8.

By suitably choosing the tappings connecting the inductance 8 to the electrodes of the valves 3, it can be arranged that the bulk of the energy of the inductance is absorbed by the valves 3 during approximately a half cycle of the natural period of the inductance 8 and its associated stray capacities. Thus, when the pulse duration is arranged to be 0.5 microsecond, the inductance 8 should tune with its associated capacities at a frequency of 1 megacycle.

In order to prevent the inductance 8 from oscillating after the initial voltage surge, a damping resistance may be provided across the inductance 8, or alternatively, a diode valve 15 may be provided shunted across part of the inductance 8 by a switch 15a and arranged to be rendered conducting as soon as the current in the inductance 8 reverses.

If desired, an additional valve 16 may be provided connected through a switch 16a to the control grid of the valve 13 to assist in rendering the valve 13 non-conducting at the required time. The valve 16 is normally non-conducting, but as soon as the valve 13 is rendered non-conducting by the switching pulse the valve 16 is rendered conducting by the high voltage impulse generated across inductance 8 due to the connection of its control electrode to the lower end of the inductance 8, and thus provides a negative pulse at its anode which is applied to the control electrode of valve 13 so ensuring that the valve 13 is held in the non-conducting state. Further, should the inductance 8 tend to oscillate for more than a half period of oscillation, the valve 16 will be rendered non-conducting and will cause the valve 13 to conduct again owing to the rise of voltage at the anode of valve 16. The damping thus applied by the valve 13 will then suppress the oscillations in the inductance 8.

In order to improve the efficiency of the operation of the valve 13 it is preferred to apply a sawtooth shaped switching signal to its control electrode. If the valve 13 is rendered fully conducting at the beginning of the 4 microsecond period, the anode potential will fall suddenly to a low value causing the screening electrode of the valve to take an undesirably high current. If, however, a sawtooth shaped switching pulse is applied to the valve 13 it can be arranged that the screen grid current is maintained small. A circuit for modifying a rectangular switching pulse of 4 microseconds' duration to a suitable sawtooth form is shown in Figure 2. The positive rectangular pulse is applied through a resistance 17 to a condenser 18 arranged in series with a diode valve 19. Shunted across the diode valve 19 is a leak resistance 20. When the positive pulse is applied the diode 19 is rendered conducting, short circuiting the resistance 20 and permitting the condenser 18 to charge negatively through resistance 17. When the positive pulse ceases the diode 19 is rendered non-conducting and the negative charge in the condenser 18 leaks away slowly through the leak resistance 20, restoring the potential of the condenser to its original value, namely, earth potential, prior to the arrival of the next positive pulse. The charge across the condenser 18 during the presence of a rectangular pulse is thus of substan-

tially sawtooth waveform and is applied through a condenser 21 and leak resistance 22 to the grid of the valve 13.

The switching pulses applied to the valves 13 or to the circuit of Figure 2 may be produced in any well known manner and may be shaped, if required, by suitable limiter stages. It is important that the valve 13 be rendered non-conducting as rapidly as possible so as to generate a high voltage across inductance 8 and to limit the power dissipated at the anode of the valve 13.

The circuit shown in Figure 1 enables very high voltages to be applied to the valves 3 far in excess of their normal rating, since the period of application of the voltages is so short that the defects that usually arise when valves are heavily overloaded are not so likely to occur. Similar remarks apply to the valve 13. Since the high voltages are of short duration the insulation of the inductance 7 will also not present serious difficulties.

Referring now to Figure 3, there is shown an alternative arrangement in which the inductance across which the high voltage impulse is developed forms part of a time delay network. Elements in this drawing corresponding to elements in Figure 1 of the drawings are given the same reference numbers. In this arrangement, the anodes of the four parallel connected valves 13 receive their polarizing voltage via the choke 23 and are coupled to the inductance 8 via the blocking condenser 24 and the inductance 26a, the purpose of which will be hereinafter explained. If desired, the choke 23 and condenser 24 may be omitted as illustrated in Fig. 4 and the D.-C. potentials in the cathode of valves 13 suitably adjusted by separate biasing means. It will be seen that a number of capacities 25 are connected between tapping points in the inductance 8 and the earthed end of the inductance 8 remote from the anodes of the valves 13, and the arrangement is such that these capacities 25 constitute with inductance 8 a time delay network.

Let it be assumed that it is desired to apply to the anodes of the valves 3 a high voltage pulse of 2 microseconds duration at intervals of 1500 microseconds, and that the valves 3 are to draw 3 amperes at 6000 volts in each 2 microsecond period. The effective load resistance will thus be 2000 ohms. In this case, the time delay network constituted by the inductance 8 and the capacities 25 should be designed to have a characteristic impedance substantially equal to 2000 ohms and a time delay substantially equal to 1 microsecond.

The arrangement operates as follows. During time periods, which may conveniently be 20 microseconds, immediately preceding the 2 microsecond periods during which it is desired to generate the high voltage impulse, the valves 13 are caused to conduct and to build up current in the inductance 8 and thereafter are suddenly caused to become non-conducting. If it is assumed that the current built up in the inductance is 6 amperes, then the interruption of this current can be regarded as equivalent to the application of a current of 6 amperes in the reverse sense when the valves 13 are rendered non-conducting. The effective application of this reverse current will be in the proper sense to raise the anodes of the valves 3 to a high positive potential and thus to cause these valves to present a 2000 ohm load and thus to provide a matched termination for the delay network. Half the applied current will therefore flow through the load provided by the valves

3 and the other half of the current will propagate along the network, be reflected at the short circuited end in similar phase and return. The voltage wave will, however, be reflected in anti-phase, so that after 2 microseconds the voltage across the valves 3 will collapse to zero and the whole of the applied current will continue to flow through the inductance 8, thus neutralizing the current built up in the inductance 8 during the 10 20 microsecond charging period and reducing the net current in the inductance 8 to zero. It will thus be seen that the network provides a high voltage pulse having a duration equal to twice the time delay of said network.

15 It will be appreciated that it is important that the load shall be of a value suitable to terminate the delay network in a substantially reflectionless manner, since otherwise reflections will occur and further voltage pulses will be applied to the load at 2 microsecond intervals, which might be disadvantageous, particularly if as shown in the drawing the valves 3 are arranged to operate as a self-maintained oscillator, as oscillations may recommence when these reflected impulses 20 arrive. The load impedance may conveniently be adjusted by alteration of the coupling between the tuned circuit 6 and the aerial coupling coil 7.

25 Although it is preferred to short circuit one end of the delay network, any terminating impedance, which in operation will give rise to reflection, may be used. In such cases, however, subsidiary voltage pulses may occur at intervals after the main pulse, and precautions, such as the provision of grid current damping, may be necessary to prevent recommencement of oscillations.

30 The voltage impulse generated by the above arrangement is substantially rectangular, which is particularly advantageous in the case of pulse transmitters for detecting the presence of reflecting objects since, as has previously been explained, the sharp fall of potential causes the oscillations to be suppressed rapidly and this enables reflecting objects at close range to be detected. It is found, however, that the sharpness 35 of the voltage impulse waveform is sometimes reduced by the capacities of the valves and the stray capacities of the circuits, etc., and it is therefore desirable to introduce inductances 26a, 26b and 26c as shown to form with these capacities a low pass filter of constant characteristic impedance and passing frequencies up to as high a frequency as possible. In general, the squareness of the pulse can be improved by giving the inductance 26a a value lying between CR^2 and $\frac{1}{2}CR^2$, where C is the effective capacity of the anode circuit of the valves 13 and R is the characteristic impedance of the time delay network. Similarly, the stray capacities 27 of the lead 28 40 through which the voltages are applied to the anodes of the valves 3 are built out by means of the inductance 26b and the effective capacity of the anode circuit of the valves 3 is built out by the inductance 26c, so that the voltage generated 45 in the time delay network may pass to the anodes of the valves 3 with only a small amount of distortion. In one practical case, the inductance 8 was split up into 20 sections and the condensers 25 were given values of 25 micromicrofarads, the 50 time delay network thus constituted having a characteristic impedance of 2000 ohms and the path between the network and the load was effectively broken up into sections of 30 micro-micromicrofarads capacity by means such as the series inductance 26b.

In order to limit the power dissipated in the valves 13 which build up the current in the inductance 8, there may conveniently be included between their screening grids and the source of polarizing voltage for said grids a resistance 29 and a parallel resonant circuit comprising the inductance 30 and the shunt capacities 31. This arrangement causes the potential of the screening grids to drop during the preliminary portion of the charging period, due to the voltage drop produced by the large screening grid current across the resistance 29, but if the resonant frequency of said circuit is suitably chosen it causes the potential on these electrodes to rise to a maximum towards the end of this period due to oscillation of the tuned circuit. In this way, the power dissipated in the valves 13 during the charging period is reduced without decreasing the current set up in the inductance 8 at the end of the charging period.

Although in the examples described above, the high voltage pulse has been applied to a load consisting of apparatus adapted to generate radio frequency oscillations upon the application of said pulse thereto, it will be understood that the load to which the pulse is applied may be of any desired form. Any number of valves may be used in parallel for building up the current in the inductance, and the high voltage may, if desired, be taken from another inductance coupled to said first-mentioned inductance.

It will be understood that, in the case of apparatus for generating short bursts of radio frequency oscillations under the control of high voltage pulses developed by apparatus according to the invention, the valves providing the radio frequency oscillations may either be self-oscillating or may serve to amplify oscillations provided by a separate source of oscillations. In the latter case, it is only necessary to arrange that radio frequency oscillations are applied to said valves during the periods when said valves are operative. In the former case, it may be desirable to include between the inductance, across which the high voltage impulses are developed, and the anodes of said valves, a resistance shunted by a condenser and adapted to provide a negative bias for the anodes of said valves so as to prevent the generation of further oscillations should additional positive pulses be generated due to oscillation of said inductance with its parallel capacity.

The invention is particularly applicable for use with valves having oxide coated cathodes, since they are capable of supplying very large currents as compared with their normal rating. Where the invention is applied to valves having so-called "bright" emitters the invention does not in general allow for a very large increase in their power output although, of course, the advantage in using the inductance and the associated elements as a means for obtaining very large high tension voltages for short periods is still present.

Although the present invention is especially applicable when it is desired only to apply operating potentials to the electrodes of valves for relatively short periods during which they are required to be operative and during which they are heavily overloaded, the invention can, however, be applied generally. For example, it may be also applied to very large power valves in which case the very large voltages contemplated in the present invention would not be regarded as being very large compared with the normal rated operating potential.

What is claimed is:

1. Apparatus for applying to a load, high voltage impulses of short duration at time intervals long in relation to said short duration, comprising at least one thermionic valve arranged so as normally to be non-conducting, an inductance connected in the output circuit of said valve, and means for causing said valve to conduct for a predetermined time period substantially shorter than said time intervals so as to build up a current in said inductance and for thereafter causing said valve suddenly to return to the non-conducting state so as to set up said high voltage impulse across said inductance, said inductance constituting the whole or part of the series inductance elements of a time delay network that is terminated at its end remote from said valve by an impedance, preferably low in value, such that in operation reflection occurs, and that is terminated at its other end in a substantially reflectionless manner by said load.

2. Apparatus according to claim 1 in which said means for causing said valve to conduct comprises a source of positive biasing pulses connected between the control electrode and cathode of said valve.

3. Apparatus according to claim 1 in which said biasing pulses are of sawtooth waveform.

4. Apparatus according to claim 1 in which said valve has an additional electrode connected to serve as a screening grid and in which there is included between said screening grid and a source of positive voltage a resistance whereby the voltage drop due to current flowing to said screening grid maintains the current in the output circuit of said valve at a low value during the preliminary portion of said predetermined time periods.

5. Apparatus for applying to a load, high voltage impulses of short duration at time intervals long in relation to said short duration, comprising at least one thermionic valve arranged so as to be non-conducting, said valve including an electrode connected to serve as a screening grid and an oscillatory circuit connected between said screening grid and a source of positive voltage whereby the voltage drop due to current flowing through said screening grid maintains a current in the output circuit of said valve at a low value during the preliminary portion of said predetermined time periods, said oscillatory circuit being so tuned that in operation due to oscillations of said circuit the voltage of said screen grid rises to a maximum towards the end of said predetermined time periods, an inductance connected in an output circuit of said valve, means for causing said valve to conduct for a predetermined time period substantially shorter than said time intervals so as to build up a current in said inductance and for thereafter causing said valve suddenly to return to the non-conducting state so as to set up said high voltage impulse across said inductance, and means for feeding said impulses to said load.

6. Apparatus for applying to a load, high voltage impulses of short duration at time intervals long in relation to said short duration, comprising at least one thermionic valve arranged so as to be non-conducting, said valve including an electrode connected to serve as a screening grid and an oscillatory circuit connected between said screening grid and a source of positive voltage whereby the voltage drop due to current flowing through said screening grid maintains a current in the output circuit of said valve at a low value

during the preliminary portion of said predetermined time periods, said oscillatory circuit being so tuned that in operation due to oscillations of said circuit the voltage of said screen grid rises to a maximum towards the end of said predetermined time periods, an inductance connected in an output circuit of said valve, means for causing said valve to conduct for a predetermined time period substantially shorter than said time intervals so as to build up a current in said inductance and for thereafter causing said valve suddenly to return to the non-conducting state so as to set up said high voltage impulse across said inductance, said inductance constituting the whole or part of the series inductance elements of a time delay network that is terminated at its end remote from said valve by an impedance, preferably low in value, such that in operation reflection occurs, and that is terminated at its other end in a substantially reflectionless manner by said load.

7. Apparatus for applying to a load, high voltage impulses of short duration of time intervals long in relation to said short duration, comprising at least one thermionic valve arranged so as normally to be non-conducting, an inductance connected in the output circuit of said valve, means for causing said valve to conduct for a predetermined time period substantially shorter than said time intervals so as to build up a current in said inductance and for thereafter causing said valve suddenly to return to the non-conducting state so as to set up said high voltage impulse across said inductance, said inductance constituting the whole or part of the series inductance elements of a time delay network that is terminated at its end remote from said valve by an impedance, preferably low in value, such that in operation reflection occurs, and that is terminated at its other end in a substantially reflectionless manner by said load, and means for feeding said impulses to said load, said means for causing said valve to conduct comprising a source of positive biasing pulses connected between the control electrode and cathode of said valve, said last means being so connected to said inductance that when in operation said high voltage impulse is generated, and means for applying an additional negative bias to the control grid of said valve so as to maintain said valve non-conducting.

8. Apparatus for applying to a load, high voltage impulses of short duration at time intervals long in relation to said short duration, comprising at least one thermionic valve arranged so as normally to be non-conducting, an inductance connected in the output circuit of said valve, means for causing said valve to conduct for a predetermined time period substantially shorter than said time intervals so as to build up a current in said inductance and for thereafter causing said valve suddenly to return to the non-conducting state so as to set up said high voltage impulse across said inductance, and means for feeding said impulses to said load, said valve having an additional electrode connected to serve as a screening grid, said apparatus including between said screening grid and a source of positive voltage a resistance whereby the voltage drop due to current flowing to said screening grid maintains the current in the output circuit of said valve at a low value during the preliminary portion of said predetermined time periods.

9. Apparatus for applying to a load, high voltage impulses of short duration at time intervals long in relation to said short duration, comprising at least one thermionic valve arranged so as normally to be non-conducting, an inductance connected in the output circuit of said valve, means for causing said valve to conduct for a predetermined time period substantially shorter than said time intervals so as to build up a current in said inductance and for thereafter causing said valve suddenly to return to the non-conducting state so as to set up said high voltage impulse across said inductance, and means for feeding said impulses to said load, said load comprising a generator for generating short bursts of radio frequency oscillations which generator includes a valve that is normally inoperative, said means for feeding said impulses to said load comprising means for applying said impulses between the anode and cathode of said generator valve so as to cause said generator valve to become operative to generate said oscillations, and wherein at least one inductance is connected between the anode of said generator valve and said first inductance so as to constitute with the stray capacities of the circuit a filter adapted to pass said impulses without substantial distortion of its waveform.

10. Apparatus for applying to a load, high voltage impulses of short duration at time intervals long in relation to said short duration, comprising at least one thermionic valve arranged so as normally to be non-conducting, an inductance connected in the output circuit of said valve, means for causing said valve to conduct for a predetermined time period substantially shorter than said time intervals so as to build up a current in said inductance and for thereafter causing said valve suddenly to return to the non-conducting state so as to set up said high voltage impulse across said inductance, and means for feeding said impulses to said load, said load comprising a generator for generating short bursts of radio frequency oscillations which generator includes a valve that is normally inoperative, said means for feeding said impulses to said load comprising means for applying said impulses between the anode and cathode of said generator valve so as to cause said generator valve to become operative to generate said oscillations, and wherein means are provided for applying a positive voltage impulse, after a time delay of the same order as the duration of each of said high voltage impulses, between the grid and cathode of said generator valve whereby said oscillations are more rapidly damped after the cessation of each of said impulse by grid current damping.
